UNITED STATES PATENT OFFICE.

SEYMOUR TROY, OF NEW YORK, N. Y.

DESIGN FOR A SLIPPER.

Application filed January 8, 1925. Serial No. 11,961. Term of patent 3½ years.

To all whom it may concern:

Be it known that I, SEYMOUR TROY, a citizen of the Republic of Russia, and a resident of the city of New York, county of Kings, and State of New York, have invented a new, original, and ornamented Design for a Slipper, of which the following is a specification, reference being had to the accompanying drawing, forming part of this specification.

The figure in the drawing shows a slipper in a side elevational view embodying my design.

I claim:

The ornamental design for a slipper as shown.

In witness whereof, I have hereunder signed my name this 22nd day of December, 1924.

SEYMOUR TROY.
